Des. 590

Thomas Ball of Boston Mass.

Assignor to
George W. Nichols of Boston Mass
Letters Patent No 590. Dated Augt 9th 1853.

The Schedule referred to in these Letters Patent and making part of the same

To all persons to whom these presents shall come:

Be it known
that I, Thomas Ball of Boston in the County of Suffolk
and State of Massachusetts have produced a new and or-
iginal design for a statuette of Daniel Webster, and I here-
by declare that the said new design is fully described and
represented in the following specification and accompan-
ying drawings to which reference is herein after made.

The figures of the accompanying
plates of drawings represent my new design, In Plate,
Fig 1. is a front view of the statuette, In Pl. 2,
Fig. 2. is a side view of the same.

2

Des. 590

_____ a a in the drawings. is the base on which the figure stands. On the side of this base and a little back of the figure is placed a column b b partially covered with drapery c c c which also extends the whole width of the base on the back. From under the drapery projects two books d d. The figure e e, f f is represented as dressed in Citizen's clothes, the coat e e buttoned up and the right hand in the breast of the same, the left arm dropping at his side. and the right leg a little advanced.

_____ Having thus described my new design I shall state my Claim as follows.

_____ What I Claim as my invention or production is the new design for a Statuette of Daniel Webster, as herein above described and represented in the drawings.
